United States Patent Office.

EDWARD L. COOKE AND JABEZ H. WHITMORE, OF HARTFORD,
CONNECTICUT.

Design No. 4,779, dated April 11, 1871.

DESIGN FOR A BURIAL-CASKET.

The Schedule referred to in these Letters Patent and making part of the same.

To all whom it may concern:

Be it known that we, EDWARD L. COOKE and JABEZ H. WHITMORE, of the city and county of Hartford and State of Connecticut, have invented or discovered a new and useful Design for a Burial-Casket; and to enable others skilled in the art to make and use the same we will proceed to describe, referring to the photographic drawings, in which the same letters indicate like parts.

In the accompanying photographic views—

A is a side view of the body of the casket, the opposite side and the ends being of the same configuration.

The shape of each side and end consists of two

members, the one convex, the other concave, forming what is commonly called an ogee, and configurated with a base molding, B.

C is a casket-cover, configurated with a raised molding, D; the object of which is to produce a plain rich design for a burial-casket.

What we claim, and desire to secure by Letters Patent, is—

The design for a coffin-body, as shown.

EDWARD L. COOKE.
JABEZ H. WHITMORE.
